CLOSING DIE FOR ROPE MAKING MACHINES

Filed Sept. 17, 1931

UNITED STATES PATENT OFFICE

PETER FRANK, OF WILKES-BARRE, PENNSYLVANIA, ASSIGNOR TO AMERICAN CABLE COMPANY, INC., A CORPORATION OF DELAWARE

CLOSING DIE FOR ROPE MAKING MACHINES

Application filed September 17, 1931. Serial No. 563,261.

This invention relates to closing dies for rope making machines and has for its primary object the provision of a closing die adapted for use in the fabrication of wire ropes.

It is well known in the wire-rope making art that ropes of a given nominal size vary slightly in diameter owing to necessary variations in diameter of the component wires and in the diameter of the core. Under conventional practice it has been necessary to have on hand several sets of "solid" dies of slightly different diameter to take care of these variations, depending on whether the component wires are running small or large, yet within their tolerance.

A particular object of the present invention is to provide a closing die which will obviate the need for maintaining on hand several sets of dies for each size of rope, the present invention providing a self-closing die which will exert a constant compressive force in closing the rope, regardless of the above described variations in size of the component wires, and/or of the core.

Another object of the invention is to provide a closing die of the above character adapted to apply uniform pressure to the entire periphery of the rope. Still another object is to provide a closing die by which a predetermined pressure can be applied to the rope at all times, compensating automatically for the aforesaid variations. Another object is to provide such a closing die with adjusting means adapted to permit the die to be used in the formation of ropes of different sizes.

Among other objects of the invention is the provision of a die, the operation of which results in the formation of a perfectly round rope having uniform spacing between the component strands; also to provide a closing die of the above type adapted to yield sufficiently to permit passage of a portion of

the rope under formation which may be of abnormal diameter.

The above and other features of the invention are illustrated and described fully in the accompanying drawing and specification and are pointed out in the claims.

In the drawing,

Fig. 1 is a view in side elevation of a closing die in the construction of which the present invention has been embodied;

Fig. 2 is a view of the same in front elevation;

Fig. 3 is a plan view of Fig. 2 showing the closing die in horizontal section on the line 3-3 of Fig. 2;

Fig. 4 is a detail view of the dies and die blocks, taken in vertical longitudinal section on the line 4-4 of Fig. 3;

Fig. 5 is a view in transverse vertical section on the line 5-5 of Fig. 4.

In a now preferred embodiment of the invention selected for illustration and description to permit ready and complete understanding of the improved closing die, the reference character 11 designates the base of the machine, which may be of any suitable shape and size to support the operating parts of the closing die proper.

In pursuance of the invention, the form of die illustrated comprises three segmental wedge-shaped sections 12, 13, and 14 mounted co-axially and movable longitudinally, in a frame comprising an upper block 15 and a lower block 16, these blocks being formed with inclined inner walls 17 adapted to be engaged by the inclined peripheries of the wedge-shaped segments, the latter forming, in their assembled relation, the frustum of a cone, and constituting the closing die proper.

Each of the blocks 15 and 16, as shown in Figs. 4 and 5, is provided with studs 18 mounted in sockets 19 and extending radially inward toward the axis of movement of the rope being formed, the latter being designated by the reference character R.

Each of the studs enters a peripheral groove 20 formed longitudinally upon one of the die sections, and thus the die sections are prevented from rotative movement around the axis of the rope, while being free to move co-axially along the same.

The die blocks 15 and 16 are preferably connected by a head 21 secured by bolts 22 extending into the blocks, the head having a central aperture 23 to pass the rope, and means for actuating the die segments to be described later herein.

As shown in Fig. 3, the die blocks are preferably provided with lateral lugs 24 adapted to be engaged with abutments 25 secured to the base by bolts 26, these abutments preventing displacement of the die under the action of the rope as it is being pulled through the die.

In further pursuance of the invention, means are provided adapted to exert a constant force upon the die sections such as to cause the latter to be urged lengthwise in a direction opposite to that of the direction of movement of the rope under formation, the resultant of this force in connection with the sliding movement of the die parts along the inclined inner surfaces 17 of the die blocks 15 and 16 being to compress the die sections upon the rope with a constant pressure.

Any suitable form of means may be provided to bring about this compressive action, and as a now preferred form of such means I have shown a spring 27 mounted upon the base, being supported by a rod 28 fixed pivotally at 29 upon a bracket 33 extending from the table 31 upon which the operating parts of the closing die are mounted.

The action of the spring is communicated to the die sections by means of a lever 36 mounted pivotally at 37 upon a bracket 38 bolted at 39 to the table 31 and having its free end 40 apertured at 41 to pass the rod 28, the end 40 being adapted for engagement by the spring 27.

The intermediate or body portion of the lever extends past the aperture 23 in the head of the die frame, and this intermediate portion of the lever is provided with a threaded socket or bearing 42, enclosed by a removable cap 43, through which extends a member 44 threaded exteriorly to engage the threaded socket part of the body portion, and having a reduced nose portion 45 adapted to extend through the aperture 23 in the die head, so that the nose bears against the ends 46 of the respective die sections. This member 44 is provided with a central bore 47 through which the rope can pass, and has a head 48 of polygonal section by which it can be rotated for adjustment in its bearing relatively to the die sections.

On the rod 28 carrying the spring is provided a handle 49 which may be screwed

along the end 30 to vary the tension upon the spring.

Preferably the spring will be of such proportions that it is adapted to permit the die segments to yield lengthwise, and so expand radially, when greatly increased friction is exerted against the die segment by a rope portion having an excessively large diameter, so that no injury will be done to the die, which will function again in a normal manner when the abnormal condition has passed.

From the above description it can readily be seen that in operation, when the rope under formation is drawn through the dies in the direction of the arrow on Fig. 3, the action of the spring 27, communicated through the lever 36 and member 44 against the ends 46 of the die sections, causes the die sections respectively to move inward radially by reason of this longitudinal movement along the inclined surfaces 17 of the die blocks 15 and 16, and thus the die sections are urged with a constant compressive action upon the periphery of the rope, tending to close the component wires uniformly into a compact rope structure having a perfectly rounded periphery, and causing the wire components to assume uniformly spaced relative positions in the rope.

This action is produced in a manner which compensates for any slight variations in the diameters of individual wires, such as are encountered in practice in the rope making art, and thus the primary object of the invention is attained and any necessity for providing several solid dies of different sizes is obviated.

By adjusting the position of the member 44 carried by the lever 36, and also by varying the tension upon the spring 27 by turning the hand wheel 49, the die may be adapted to operate upon rope of different sizes without changing the dies.

I claim:

1. A closing die of the class described; comprising a plurality of die segments, a support in which said segments are mounted around the axis of formation of a rope, and actuating means to urge said die segments simultaneously toward the path of the rope to compress the rope under formation, said die segments and support respectively having co-operatively inclined surfaces adapted to cause radial approach of said segments toward the rope when moved longitudinally in one direction, and said actuating means comprising a spring connected with said segments.

2. A closing die of the class described; comprising a plurality of wedge-shaped die segments, die blocks having inclined surfaces between which said segments are mounted around the axis of formation of a rope, and actuating means to urge said die segments along the axis of said rope thereby to cause

radial approach of said segments simultaneously toward the path of the rope to compress the rope under formation.

3. A closing die of the class described; comprising a plurality of die segments, a support in which said segments are mounted around the axis of formation of a rope, and actuating means to urge said die segments simultaneously toward the path of the rope to compress the rope under formation, said actuating means comprising a connecting member adapted to bear against one end of each of said die segments, a lever adapted to operate said connecting lever, and a spring adapted to actuate said lever.

4. A closing die, as set forth in claim 3, and further characterized by having said connecting member formed as a cylinder with a threaded periphery mounted in a threaded seat in said lever, for adjustment toward and away from said die segments, whereby the extent of longitudinal movement of the latter may be varied.

5. A closing die of the class described; comprising a plurality of die segments, a support in which said segments are mounted around the axis of formation of a rope, and actuating means to urge said die segments simultaneously toward the path of the rope to compress the rope under formation, said actuating means comprising a connecting member adapted to bear against one end of each of said die segments, a lever adapted to operate said connecting lever, and a spring adapted to actuate said lever, and means to vary the tension upon said spring.

6. A closing die of the class described comprising a plurality of wedge-shaped die segments; and die blocks in which said segments are mounted around the axis of formation of a rope in position to be engaged frictionally with the periphery thereof; said die segments and die blocks respectively having inclined surfaces adapted to be mutually engaged so that upon movement of the die segments along the axis of the rope, in a direction opposite to the direction of movement of the rope under formation, said segments will mutually approach the periphery of the rope; and means to urge said die segments constantly in such opposite direction simultaneously thereby to cause a corresponding constant compressive action upon the periphery of the rope.

7. A closing die of the class described comprising a plurality of wedge-shaped die segments; and die blocks in which said segments are mounted around the axis of formation of a rope in position to be engaged frictionally with the periphery thereof; said die segments and die blocks respectively having inclined surfaces adapted to be mutually engaged so that upon movement of the die segments along the axis of the rope, in a direction opposite to the direction of movement of

the rope under formation, said segments will mutually approach the periphery of the rope; and means to urge said die segments constantly in such opposite direction simultaneously thereby to cause a corresponding constant compressive action upon the periphery of the rope, said means comprising a spring connected with the die segments.

8. A closing die of the class described comprising a plurality of die segments, and die-blocks having inclined surfaces between which said segments are mounted around the axis of formation of a rope, so that upon movement of the die segments along the axis of the rope in a direction opposite to that of formation of the rope, said segments will mutually approach the periphery of the rope under formation; and means comprising a spring connected with the die segments and acting to urge the same constantly in a direction opposite to that of the movement of the rope, but adapted to permit said segments to yield longitudinally and expand radially upon abnormal increase of friction between the periphery of the rope and said segments.

In testimony whereof, I have signed this specification.

PETER FRANK.
